MACHINE FOR OPERATING UPON
SHOE SOLESEugene J. Ray, Beverly, Mass., assignor to United
Shoe Machinery Corporation, Flemington, N. J.,
a corporation of New Jersey

Application May 23, 1946, Serial No. 671,862

8 Claims. (Cl. 12—77)

1

This invention relates to machines for operating upon unattached shoe soles and it is herein disclosed as embodied in a machine for performing such operations as edge setting or edge trimming. In machines of this character it is desirable to feed the sole with its periphery pressed against an operating tool or against both an operating tool and an edge gage. In some cases also the sole may be fed with its periphery pressed against an edge gage while the tool operates upon the marginal portion of the upper or lower face of the sole. Inasmuch as the thickness of the sole at its periphery varies locally from relatively thick in the forepart to relatively thin in the shank portion, the pressure which is developed against the periphery of the sole by the tool or the edge gage should be varied accordingly. For example, the pressure which is suitable for the relatively thick forepart might in some cases cause the relatively thin shank portion to buckle or curl over. The feeding device should, therefore, be controlled in response to the local variations in thickness of the sole.

For an example of a machine having a work feeding mechanism of this type, reference may be had to United States Letters Patent No. 2,357,337, granted on September 5, 1944, upon the application of Harry Lyon. This machine is provided with a driven feed wheel which is so arranged as not only to advance the work past an edge-setting tool but also to urge the periphery of the sole against the tool to develop the necessary operating pressure. This feed wheel is controlled by a device responsive to the thickness of the peripheral portion of the sole to vary the degree of pressure exerted upon the sole. The controlling device disclosed in the patent to Lyon is actuated by the edge-setting tool itself, which is of special construction to enable it to respond to variations of thickness, and it operates to apply to the feed wheel at the thicker portions of the sole an additional force derived from a solenoid.

It is an object of the present invention to provide a machine having the desired feeding characteristics which is simpler in construction than previous machines and in which the additional feeding force is applied more yieldingly and also in which the control of the additional force is effected directly by the rise and fall of the feed wheel without requiring a tool of special construction. In accordance with a feature of the invention, the additional force is derived from a spring thereby rendering the feeding action at all times yielding. As shown herein the feed wheel

2

is held down against the sole by a compression spring arranged at all times to exert downward pressure regardless of the thickness of the work and it is also held down throughout the upper range of rising and falling movement of the feed wheel by the added pressure of a second compression spring which, however, is not operable upon the feed wheel throughout the lower range of its rising and falling movement.

10 These and other features of the invention will best be understood from a consideration of the following specification taken in connection with the accompanying drawings, in which

Fig. 1 is a side elevation partly in section of an 15 illustrative machine embodying the invention; Fig. 2 is a plan view of the machine shown in

Fig. 1;

Fig. 3 is a front elevation of the machine;

Fig. 4 is an elevation of a portion of the 20 machine adjacent to the operating tool looking in the direction of the axis about which the work table may be tilted;

Fig. 5 is a sectional view taken on the line 25 V—V of Fig. 1;

Fig. 6 is a view in axial section of a heating unit in relation to an edge setting tool; and

Fig. 7 is a plan view showing a sole on the work 30 table engaging the operating tool and the edge gage.

35 The work engaging instrumentalities of the illustrated machine consist of a tool 20, a feed wheel 22, an edge gage 24, and a work table 26. The tool 20 may be either an edge trimming cutter or an edge setting tool, or it may be any other type of tool designed for operation upon the periphery of an unattached shoe sole; it is shown in Figs. 1, 2 and 3 as an edge trimming cutter. The feed wheel 22 is arranged to advance the work while at the same time holding it against both the tool 20 and the edge gage 24 with a definite pressure. The direction of feed of the work piece is determined by both the tool 20 and the edge gage 24, and the direction of movement of that portion of the feed wheel which engages

40 the work piece is oblique to the direction in which the work piece is constrained to travel. Because of this obliquity the force exerted upon the work piece by the feed wheel may be resolved into two components, one of which lies in the direction of feed and the other of which is so directed

45 as to cause the work piece to press against the tool 20 and the edge gage. The second component is often referred to as a component of cross feed. The feed wheel 22 is provided with 50 edged teeth 28 adapted to cut into the surface

of the work piece and thereby obtain a feeding grip upon it. The teeth 28 are not parallel to the axis of the feed wheel but lie in planes which are inclined to the axis, each at an angle of about 15°.

The supporting structure of the illustrated machine comprises a hollow frame or housing 30 shown fragmentarily in the drawings. Upon the frame 30 are mounted a gear case 32 and a bracket 34 for purposes which will hereinafter be explained.

The tool 20 and the feed wheel 22 are both driven from a source of power, not shown herein, which may for example consist of a motor housed within the frame 30. The drive is conducted to the operating members by a belt 36 running over a pulley 38 which is secured upon a horizontal shaft 40. A second pulley 42 secured upon the shaft 40 drives a sharpening device through a belt 44. This sharpening device, which is not shown herein and which is of no interest in connection with the present invention, may be used to grind the teeth of an edge trimming cutter. The shaft 40 is journaled in bearings 46 secured in the gear case 32. Secured upon the shaft 40 is a spiral gear 48 which drives a spiral gear 50 secured upon a vertical shaft 52 journaled in bearings 54 in the gear case 32. Secured upon the upper portion of the shaft 52 is a worm 56 which drives a worm wheel 58 mounted on a horizontal shaft 60 journaled in bearings 62 in the gear case 32. The shaft 60 through a universal coupling 64 drives a shaft 68 upon the outer end of which is secured the feed wheel 22.

Upon the lower end of the shaft 52 is a pulley 70 which drives a belt 72 running over a pulley 74. Journaled in bearings 76 in the bracket 34 is a vertical shaft 78 upon the lower end of which the pulley 74 is mounted. The tool 20 is secured upon the upper end of the shaft 78. It is sometimes necessary when changing from one source of power to another, or when substituting for the tool 20 a tool of different character, to vary the speed ratio between the pulleys 74 and 70. This may require an adjustment of the shaft 78 toward or from the shaft 52 and in order to accommodate such adjustment the bracket 34 is clamped to the frame 30 by screws 80 extending through slots 82 in the base of the bracket 34. A tongue 84 (Fig. 3) depending from the bracket 34 engages a guideway 85 (Fig. 5) on the frame 30 to maintain the bracket 34 in proper alignment while it is being adjusted.

In order to maintain a predetermined relation between the feed wheel 22, the edge gage 26 and the tool 20, notwithstanding the adjustment of the bracket 34, the feed wheel and the edge gage as well as the tool are all supported by the bracket 34. To provide for such support of the feed wheel and the edge gage a right angle bracket 86 (Fig. 5) having a tongue and groove connection 88 with a lug 89 on the bracket 34 is clamped to the lug 89 with provision for horizontal adjustment in a direction transverse to the axes of the shafts 40 and 60 by a screw 90 extending through a horizontal slot 91 in the bracket 86. Extending upwardly from the bracket 86 and secured thereto by a clamping screw 92 is a bracket 94. A tongue and groove connection 96, between the bracket 94 and the bracket 86, guides the bracket 94 for horizontal adjustment in a direction parallel to the axes of the shafts 40 and 60. The clamping screw 92, passing through a slot 98 in the bracket 86 to accommodate such adjustment, secures the bracket 94 in adjusted position. Upon the upper end of the bracket 94 is formed a head 100 in the

form of a horizontally extending plate against the lower face of which is secured a bracket 102. A fulcrum pin 104, in the form of a shouldered stud upon which is thereaded a clamping nut 105, permits limited angular adjustment of the bracket 102 about a vertical axis relatively to the head 100. The bracket 102 can be secured in a desired position of such adjustment by a clamping screw 106 threaded into the bracket 102 and passing through an arcuate slot 108 formed in the head 100. The clamping screw 106 is provided with a handle 110 to facilitate turning. Depending from the bracket 102 are a pair of spaced ears 112 (one of which is seen in Fig. 1) which support a pair of diametrically opposed trunnion pins 114 (see also Fig. 2) upon which is pivotally mounted a yoke-shaped frame 116 which is formed to provide a bearing sleeve 118 for the shaft 68 which carries the feed wheel 22. By reason of this construction the frame 116 is free to swing up and down about the axes of the trunnion pins 114 enabling the feed wheel 22 to rise and fall in accordance with variations in the thickness of the work piece. The frame 116 may also be adjusted horizontally about the axis of the pin 104, thereby enabling the feed wheel 22 to be adjusted toward or from the tool 20. The purpose of this adjustment is to enable the feed wheel to be positioned close to the tool during the operation, and to be moved out of the way of the tool when the tool is being removed or replaced. A guard 120 extending partly around the feed wheel 22 is secured to the bearing sleeve 118 by screws 122.

The mechanism for yieldingly holding the feed wheel 22 down upon the work piece comprises a pair of compression springs 124 and 126 (Fig. 3) arranged in parallel vertical bores formed in a lug 128 extending upwardly from the head 100 of the bracket 94. The lower end of the spring 124 bears against a head 130 formed on a plunger 132 which extends downwardly through the bottom of the lug 128. The lower end of the spring 126 similarly bears against a head 134 formed on a plunger 136 extending downwardly through the bottom of the lug 128. Threaded downwardly into the bore which houses the spring 124, and surrounding the upper portion of that spring, is a hollow screw 138 having a knurled head 140. The screw 138 when turned adjusts the compression of the spring 124. A similar screw 142 having a knurled head 144 is provided for adjusting the compression of the spring 126. Threaded into the bearing sleeve 118 beneath the plunger 132 is a screw 146 having an enlarged head 148 which serves as an abutment for the lower end of the plunger 132. A similar screw 150 having an abutment head 152 is threaded into the bearing sleeve 118 beneath the plunger 136. The screws 146 and 150 may be turned by inserting a suitable tool in radial holes formed in their heads, the adjustment being such as to provide for engagement of the plunger 132 with the head 148 whenever a work piece, however thin, is resting on the work table 26. The head 152 of the screw 150 is adjusted somewhat lower to avoid engagement with the plunger 136 except when the feed wheel 22 bears upon a portion of the work piece having a predetermined thickness. In order to limit the downward movement of the feed wheel 22 under the influence of the spring 124 and thereby to prevent engagement of the feed wheel with the work table when there is no work piece on the work table, there is provided a stop screw 154 (Fig. 1) threaded through a lug 156 extending horizontally from the bracket 94. The lower

end of the screw 154 is provided with a knurled head 158 and the upper end bears against an under surface of the bearing sleeve 118.

Extending laterally from the bearing sleeve 118 is a lug 160 (Fig. 2) in which is formed a slot 162 extending parallel to the axes of the shafts 40 and 60. Adjustably clamped in any desired position in the slot by a screw 164 is a lever 168 from one end of which depends the edge gage 24. The opposite end of the lever 168 is in the shape of a sector and in it is formed an arcuate slot 170 which is coaxial with the screw 164. A clamping screw 172 extending through the slots 170 and 162 clamps the lever 168 in any desired position of angular adjustment about the screw 164 thereby securing the edge gage 24 in a position of desired adjustment toward or from the tool 20. The screws 164 and 172 are both threaded at their lower ends into a clamping block 173.

The work table 26 (see Fig. 4) has secured against its under face by countersunk clamping screws 174 a depending bracket 176 which has an arcuate tongue 178 engaging an arcuate groove 180 formed in a bracket 182. The axis of the arc of the tongue 178 and the groove 180 lies in the upper surface of the work table 26 and extends at an angle of about 45° to the longitudinal center line of the machine. This axis passes just within the periphery of the tool, being almost tangent to the tool, at the locality at which the operation is performed. The work table 26 may be secured in any desired position of angular adjustment about this axis by a clamping screw 184 threaded into the bracket 182 and extending through an arcuate slot 186 formed in the bracket 176. The work table 26 may therefore be secured in a horizontal position as shown in the drawings or it may be adjusted to a position of downward tilt about said axis. The work table 26 extends close to the tool 20, having an arcuate portion cut out to accommodate the tool with a minimum of clearance. This portion of the work table is formed with an undercut bevel, indicated on Fig. 4 by the reference numeral 187, to enable it to clear the tool when the table is tilted. The bracket 182 has a tongue 188 which engages a complementary groove formed in a lug 190 extending laterally from the bracket 34, this tongue and groove arrangement serving to guide the bracket 182 for heightwise adjustment on the bracket 34. A clamping screw 192 extending through a slot 194 in the bracket 182 and threaded into the lug 190 secures the bracket 182 in any desired position of heightwise adjustment. A screw 196 threaded downwardly into the bracket 34 and having a knurled head 198 which engages a notch formed in the bracket 182 enables the bracket 182 to be adjusted conveniently up or down when the clamping screw 192 is loosened.

In Figs. 4 and 6 the operating tool is shown as an edge setting tool 20' in place of the trimming cutter 20. The edge setting tool 20' has a hub 199 which fits the reduced upper end portion of the shaft 78, and it has an annular operative portion 201 which is of greater diameter than the hub. This operative portion 201 is integral with the hub and it extends from the upper end thereof. The edge setting tool 20' is clamped upon the shaft 78 by a screw 200 and by a washer 202 which bridges the annular space between the shaft 78 and the annular portion 201 of the tool; by tightening the screw 200 the hub 199 is urged against a shoulder on the shaft 78.

Some edge setting tools must be heated, and to provide for such tools the illustrated machine

is equipped with an annular heating element 204 in which are embedded electrical resistance members 206 supplied by electrical leads 208. The heating element 204 is below and coaxial with the tool 20', surrounding the hub 199 with a clearance space between it and the hub. The heating element 204 is mounted upon a horizontal plate 210 by means of tabs 212 extending inwardly from a cylindrical shield 214 which surrounds the heating element and which is secured to the plate by screws 216. The tabs 212 hold the element 204 down upon spacing flanges of pins 213, the reduced upper ends of which hold the element 204 against horizontal displacement. The plate 210 has a depending portion which is secured to the bracket 34 by screws 218. Heat is transferred from the unit 204 to the tool 20' by direct radiation to the under surface of the tool, by radiation to the hub 199 and thence by conduction to the operative portion of the tool, and also by convection induced by the blower effect of the rapidly rotating tool. The under surface of the tool, by frictional engagement with the adjacent air, will cause this air to rotate and to be thrown tangentially thereby creating a suction which draws air through the annular passageway between the hub 199 and the inner surface of the heating unit 204. The blower effect of the tool is more pronounced in the case of a tool which, as shown herein, is slotted radially, the air within the narrow radial slots being caused to rotate positively with the same angular velocity as the tool itself and thereby setting up a relatively strong suction. It will be noted that the entry of cold air from above is blocked by the washer 202. The direction of the currents of heated air is indicated by arrows on Fig. 6.

The operation of the machine will now be explained. A sole S (Fig. 7) is placed upon the work table 26 in engagement with the edge gage 24 and the tool 20 or 20'. The direction of rotation of the tool and the direction of feed of the work are indicated by arrows. As the work piece is introduced under the feed wheel 22 the feed wheel rises to the extent of the thickness of the work piece. The rotation of the feed wheel not only advances the work piece past the tool but also holds the periphery of the work piece against both the edge gage and the tool. The obliquity of the teeth of the feed wheel enables the work piece to slip relatively to the teeth, thereby avoiding a positive feeding action against the tool which might, in the case of very pointed toes or narrow heels, result in gouging out the surface of the sole. The cuts made by the feed wheel teeth in the flesh surface of the sole S are indicated by the reference character C. The force with which the sole is pressed against the tool depends upon the pressure of the feed wheel against the sole. This pressure is derived from the spring 124 and also for the thicker portions of the sole from both springs 124 and 126. As the feed roll rises in response to variations in thickness of the work piece it will cause the head 152 of the screw 150 to engage the plunger 136 thereby adding the force of the spring 126 to that of the spring 124. Such additional pressure will increase the component of cross feed to an extent which is desirable when operating upon the thicker portions of the work piece at the forepart of the sole. However, such pressure would be excessive for the relatively thin shank portion of the sole and might cause the margin of the sole to buckle or curl over. Accordingly, when the thinner portion of the sole is reached, the feed wheel drops suffi-

ciently to enable the head 152 to fall away from the plunger 136, thereby relieving the feed wheel of such additional pressure.

Having thus described my invention, what I claim as new and desire to secure by Letters Patent of the United States is:

1. In a machine for operating on shoe soles, a support for a sole, a member engageable with the periphery of the sole, a feeding device operating upon the upper face of the sole to advance the sole and also to press the sole against said periphery engageable member, means for holding said feeding device down against the upper face of the sole, a spring, and means responsive to the local thickness of the sole for imposing upon said feeding device an additional downward pressure derived from said spring, thereby increasing the pressure between the sole and the periphery engageable member, at those portions of the sole which are relatively thick.

2. In a machine for operating on shoe soles, a support for a sole, a member engageable with the periphery of the sole, a feeding device operating upon the upper face of the sole to advance the sole and also to press the sole against said periphery engageable member, said feeding device being mounted to rise and fall in accordance with variations in the local thickness of the work piece, a spring constructed and arranged to press said feeding device down against the upper face of the sole, a second spring constructed and arranged to impose additional pressure upon the feeding device, and means for limiting the action of the second spring to those portions of the sole which are relatively thick and for preventing the second spring from imposing its additional pressure when the feeding device engages portions of the sole which are relatively thin.

3. In a machine for operating on shoe soles, a work table, a member engageable with the periphery of a sole on said work table, a feed wheel engageable with the upper face of the sole on the work table for advancing the sole and also pressing the sole against said tool, a carrier for said feed wheel mounted for rising and falling movement of the feed wheel in accordance with local variations in the thickness of the sole, yieldable means acting on the carrier to hold the feed wheel down upon the sole, and yieldable means engageable with the carrier as the carrier moves upwardly into the upper range of its rising and falling movement to cause the feed wheel to bear with additional pressure upon relatively thick portions of the sole, the second mentioned yieldable means being disengageable from the carrier as the carrier moves downwardly into its lower range of rising and falling movement.

4. A machine for operating on shoe soles comprising a work table, a tool operable upon the periphery of a sole on the work table, a feed wheel engageable with the upper face of the sole on the work table, said feed wheel being mounted for rising and falling movement in accordance with local variations in the thickness of the sole and being constructed and arranged to advance the sole and also to press the periphery of the sole against said tool, a pair of compression springs constructed and arranged to press the feed wheel down against the sole, and means for limiting the expansion of one of said springs and thereby relieving the feed wheel of the pressure of that spring when the feed wheel is in a relatively low position by reason of its engagement with a relatively thin portion of the sole.

5. A machine for operating on shoe soles com-

prising, a work table, a tool operable upon the periphery of a sole on the work table, a feed wheel engageable with the upper face of the sole on the work table for advancing the sole and also pressing the periphery of the sole against said tool, a carrier for said feed wheel mounted for rising and falling movement of the feed wheel in accordance with local variations in the thickness of the sole, a pair of compression springs constructed and arranged to bear downwardly upon the feed wheel carrier to press the feed wheel down against the sole, means for limiting the downward expansion of each of said springs, said limiting means being adjustable independently for each spring, thereby enabling the limiting means to be so adjusted as to permit one spring to follow the feed wheel carrier throughout its full range of rising and falling movement and to permit the other spring to follow the feed wheel carrier throughout only the upper portion of the range of rising and falling movement of the feed wheel carrier, and a stop engageable with the feed wheel carrier to limit extreme downward movement of the feed wheel carrier and thereby to prevent contact of the feed wheel with the work table in the absence of a sole.

6. In a machine for operating on shoe soles comprising a tool operable upon the periphery of a sole, a frame, a driving member supported by said frame, driving connections from said driving member to said tool, a work feeding device constructed and arranged to advance a sole, and also to hold the periphery of the sole against said tool, and a common support for said tool and said work feeding device, said common support being mounted on said frame with provision for adjustment toward and from said driving member to accommodate driving connections of greater or less speed ratio, the work feeding device and the tool being maintained in predetermined relation, notwithstanding such adjustment, by reason of their being carried by said common support.

7. In a machine for operating on shoe soles comprising a tool operable upon the periphery of a sole, a frame, a driving member supported by said frame, driving connections from said driving member to said tool, a work table, a feed wheel for advancing a sole and also for holding the periphery of the sole against the tool, a common support for said tool, said feed wheel, and said work table, said common support being mounted on said frame with provision for adjustment toward and from said driving member to accommodate driving connections of greater or less speed ratio while the tool, the work table, and the feed wheel are maintained in predetermined relation, notwithstanding such adjustment, by reason of their being carried by said common support, and driving connections from said driving member to said feed wheel constructed and arranged to accommodate adjustment of the common support toward and from the driving means.

8. A machine for operating on shoe soles comprising a work table, a tool operable upon the periphery of a sole on the work table, a feed wheel engageable with the upper face of the sole on the work table for advancing the sole and also pressing the periphery of the sole against said tool, a shaft on which said feed wheel is mounted, means for driving said shaft, a carrier in which said shaft is journaled for rotation, a bracket on which said carrier is trunnioned for rising and falling movement of the feed wheel in accordance

with local variations in the thickness of the sole, resilient means acting upon the carrier to hold the feed wheel down upon the work, and a support upon which said carrier is pivotally mounted for angular adjustment to enable the feed wheel to be moved from an operating position close to the tool to an out-of-the-way position removed from the tool to facilitate removal and replacement of the tool.
